(57) CLAIM

An ornamental design for lighting system for an outboard motor for boats, as shown and described.

DESCRIPTION

FIG. 1 is a right side rear perspective view of lighting system for an outboard motor for boats according to our new design; FIG. 2 is a left side front perspective view thereof;

FIG. 3 is a rear elevation view thereof;

FIG. 4 is a front elevation view thereof;

FIG. 5 is a right side elevation view thereof;

FIG. 6 is a left side elevation view thereof; and,

FIG. 7 is a top plan view thereof.

The broken lines are for illustrative purposes only and form no part of the claimed design.
